METAL BAFFLE FOR WINDOW SASH

Martin W. Hilgendorf, Stevens Point, Wis., assignor to Vetter Manufacturing Co., Stevens Point, Wis., a corporation of Wisconsin

Filed Dec. 6, 1954, Ser. No. 473,083

3 Claims. (Cl. 20—52.2)

This invention relates generally to window construction and more particularly to a novel baffle for use as weather stripping in a removable window construction.

The primary object of the present invention resides in the provision of means for preventing the infiltration of air through the pocket behind the floating channels in a removable window construction.

A further object of the invention resides in the provision of a baffle for insuring smoother operation of removable windows by preventing the parts of adjacent floating channels from climbing or sticking after being depressed in the operation of removing a sash.

The construction of this invention features a baffle which is resiliently engageable within the saw kerf or groove in the jamb of a window. The hook portion of the strip properly holds the strip in position so that a wing portion thereof can extend between adjacent floating channels. The strip is held in alignment by the locking action of the hook portion and by the central portion of the strip which lies flush with the jamb.

Further objects and features of this invention reside in the provision of a baffle for use in conjunction with removable windows that is simple in construction, highly efficient in operation, and inexpensive to produce thereby permitting wide distribution and utilization.

These, together with the various ancillary objects and features of the invention which will become apparent as the following description proceeds, are attained by this baffle for use in removable window construction, a preferred embodiment of which has been illustrated in the accompanying drawings, by way of example only, wherein:

Figure 1 is an elevational view of a removable window construction employing a baffle with parts of the window jamb and molding being broken away to show parts in section for greater clarity;

Figure 2 is an enlarged horizontal sectional detail view as taken along the plane of line 2—2 in Figure 1;

Figure 3 is an enlarged sectional detail view illustrating the manner in which the hook portion of the baffle is engaged in the saw kerf or groove in the jamb of the window; and

Figure 4 is a perspective view of the elongated strip which forms the baffle for the floating channels.

With continuing reference to the accompanying drawings wherein like reference numerals designate similar parts throughout the various views, reference numeral 10 generally designates a removable window construction which includes upper and lower sash 12 and 14 mounted on pairs of floating channels 16 and 18 secured by fasteners as at 20 and 22 to the jamb 24.

As can be seen best in Figure 2, springs 26 and 28 concentrically disposed about the fasteners 20 and 22 yieldingly engage the floating channels 16 and 18 and the jamb 24 to urge the floating channels 16 and 18 outwardly into engagement with the sash 12 and 14. The floating channels 16 and 18 are of course provided with

2

projecting portions 30 and 32 which seat within grooves 34 and 36 in the sash.

Even through suitable moldings as at 38, 40, 42 and 44 are positioned about the window opening, air may 5 readily pass through the space 46 between the floating channels 16 and 18 and the jamb 24.

In order to prevent the passage of air from outside the building in which the window 10 is utilized to the inside thereof, the metallic baffle formed of the strip 10 generally designated by reference numeral 50 is utilized. As can be seen best in Figure 3, the strip 50 includes a central portion 52 adapted to lie flush with the inner surface of the jamb 24. The strip 50 has a hook portion 54 receivable in a saw kerf or groove 56 formed 15 in the jamb 24 with the hook portion resiliently engaging and lockingly holding the strip 50 in alignment with the central portion 52 held flush with the jamb 24. It is to be noted that the hook portion 54 digs into the wooden jamb 24 and no further fasteners are necessary 20 to hold the strip 50 in position.

At the other edge of the central portion 52 there is provided a wing 58 which extends between the floating channels 16 and 18 and has an edge portion 60 bent back upon itself to both rigidify the strip 50 and to 25 fill the space between the floating channels 16 and 18 while providing a bearing surface for the side faces of the floating channels 16 and 18 thereby assuring during the operation of removal of one of the sashes 12 and 14, the floating channels 16 and 18 will not 30 bind or climb upon each other to thereby prevent proper operation of the sash or to permit ingress of air from the outside to the inside of the building in which the window construction 10 is utilized to insure against loss of heat.

35 It is believed that it can be readily seen that the strip 50 will serve to provide a baffle against the ingress of air from the outside of a building through the window 10 between the floating channels 16 and 18 and the jamb 24 by blocking this passage completely. Further, the 40 strip 50 serves to insure proper operation of the window sash 12 and 14.

From the foregoing, the construction and operation of the device will be readily understood and further explanation is believed to be unnecessary. However, since 45 numerous modifications and changes will readily occur to those skilled in the art, it is not desired to limit the invention to the exact construction shown and described, and accordingly all suitable modifications and equivalents may be resorted to, falling within the scope of the 50 appended claims.

What is claimed as new is as follows:

1. A window construction including a baffle for use as a weather strip for removable windows, said window construction comprising floating sash channels, fasteners secured to a window jamb, said sash channels being 55 movably mounted on said fasteners, springs centrally disposed on said fasteners yieldingly engaging said window jamb and said sash channels resiliently urging said sash channels away from said jamb, an elongated strip 60 having a central portion lying flush with said window jamb, said jamb having a groove therein forming a pair of parallel inner faces on opposite sides of said groove, said strip having a wedge portion received in said groove, said strip having a wing extending between said floating 65 sash channels, said wedge portion being resiliently engaged in said groove and lockingly engaging both of said pair of faces formed in said jamb to hold said strip in position, said wedge portion terminating in a free edge biting into one of said faces, said wing having an edge portion bent back upon itself to hold said floating channels apart and in position while rigidifying said strip,

said floating channels being spaced apart a distance equal to the thickness of said edge portion.

2. A double hung, vertically slideable window sash structure comprising a window frame including a side frame member, inner and outer sash guides extending substantially the full length of said side frame member and mounted for yielding transverse movement relative thereto, said sash guides having adjacent side edge portions disposed in proximate face-to-face relation, and a unitary baffle strip disposed between said side frame member and said sash guides, said baffle strip comprising an elongated, thin strip of spring material having an intermediate seating web, a pair of leg flanges extending in opposite directions respectively from opposite end portions of said seating web, and the outer edges of each of said leg flanges having rebent flange portions, the rebent flange portion of one leg diverging from said one leg flange, said side frame member including a rabbet extending longitudinally thereof and receiving the rebent flange portion of said one of said leg flanges of said baffle strip in pressing engagement therewith so as to secure said baffle strip to said side frame member with said seating web disposed against said side frame member, whereby the other of said leg flanges extends away from said side frame member toward said sash guides with the outer end of said other leg flange and the rebent flange portion thereof disposed between and in engagement with said adjacent side portions of said sash guides.

3. A slideable window sash structure comprising a window frame including a frame member, inner and outer sash guides extending along said frame member and mounted for yielding transverse movement relative

thereto, said sash guides having adjacent side edge portions disposed in proximate face-to-face relation, and a unitary baffle strip disposed between said frame member and said sash guides, said baffle strip comprising an elongated, thin strip of spring material having an intermediate seating web, a pair of leg flanges extending in opposite directions respectively from opposite end portions of said seating web, and the outer edges of each of said leg flanges having rebent flange portions, the rebent flange portion of one leg diverging from said one leg flange, said frame member including a rabbet extending longitudinally thereof and receiving the rebent flange portion of said one of said leg flanges of said baffle strip in pressing engagement therewith so as to secure said baffle strip to said frame member with said seating web disposed against said frame member, whereby the other of said leg flanges extends away from said frame member towards said sash guides with the other end of said other leg flange and the rebent flange portion thereof disposed between and in engagement with said adjacent side portions of said sash guides.
